COMBINATION BOX AND DISPLAY STAND

Ernest Varrieur, Attleboro, Mass., assignor to Babcock Box Co., Inc., a corporation of Massachusetts

Application March 6, 1958, Serial No. 719,674

2 Claims. (Cl. 206—16)

This invention relates to boxes and more particularly to a box for holding and displaying electric shavers.

In the case of jewelry and other personal items such as electric shavers, it has long been recognized that the containers for such items should not only serve to house and protect the items during shipment, but should also be decorative and effective as a means for displaying the goods in the retailers' establishments. However, the cost for packaging any item cannot be ignored, and, accordingly, manufacturers strive to provide containers that are attractive but compact and inexpensive to manufacture.

Electric shavers present somewhat of a problem since the box or case must (1) house the shaver, (2) house the electric cord for the shaver, and (3) function as a display stand for the shaver. Heretofore the practice has been to make the box or case large enough to hold the cord in wound-up form side by side with the shaver, it being understood that reference is had to a shaver having a detachable cord, as is the usual practice. This has two disadvantages. First of all, the cord itself attracts attention, thereby detracting from the beauty of the shaver per se. Secondly, in order to keep the case as small as possible, the space provided for the cord is made just large enough to accommodate the cord only when the latter is wound up in a predetermined manner which has been carefully worked out by the manufacturer. The latter requirement aggravates not only the purchasers but also the dealers or salesmen who are required to demonstrate the shaver. In most cases, the purchaser is reluctant to spend a lot of time winding the cord in a precise manner and so he either places only the shaver in the box, in which case the cord may easily become lost or misplaced, or else both the shaver and cord are put into the box in helter-skelter arrangement whereby the cord may prevent the cover from closing fully, in which case the shaver may become dusty or affected by moisture or easily knocked onto the floor and damaged.

Accordingly, the primary object of this invention is to provide a box or case for an electric shaver and the electric cord therefor which is so designed that only the shaver is visible when the cover is opened.

It is a further object of this invention to provide a box or case for an electric shaver which contains a hidden compartment for housing the electric cord of the shaver, the cord compartment being so designed that the cord can be easily stored in the compartment.

Still another object is the provision of a box of the character described wherein the cord compartment does not materially increase the overall size of the box and wherein the shaver is displayed in a highly attractive manner.

Other objects and many of the attendant advantages of this invention will become more readily apparent as reference is had to the following detailed description when considered together with the accompanying drawings wherein:

Fig. 1 is a front view in elevation of a box embody-

2

ing the present invention, the box being shown with the cover closed;

Fig. 2 is a perspective view of the same box with the cover open to reveal the element which supports the shaver for display;

Fig. 3 is a sectional view of the same box with a shaver and electric cord stored therein, the section being taken along line 3—3 of Fig. 1; and

Fig. 4 is a perspective view of the element which functions as a display stand for the shaver and as a storage compartment for the electric cord, the element being shown with its bottom side up.

Referring now to Figs. 1, 2 and 3 specifically, the present invention comprises a box or case comprising a bottom 2 and a cover 4, both of which may be made of sheet metal provided with a leather or leatherette covering, a plastic or a suitable paper material, such as cardboard or a plastic impregnated paper. In the illustrated embodiment, the bottom part 2 of the box has an interior liner 6 covering its bottom and another liner 8 covering its vertically extending wall. Correspondingly, the top and side walls of the cover 4 are lined with liner elements 10 and 12, respectively. These liners may be made of cardboard or other suitable material. Preferably, the surface of the liner material is coated with flocked velour. The cover of the box is provided with a spring catch 14 which engages and locks with a suitable projection or locking tab 16 on the bottom portion 2 of the box. For convenience in carrying, the illustrated box is provided with a flexible strap 20 which is fixed to a suitable metal terminal element 22 which is pivotally secured to the latch means 14.

It is preferred that a portion of the side wall of the bottom of the box be flat. In this case, the flat wall portion is identified by the numeral 26 and is located at the rear end of the box. The purpose of the flat surface 26 is to locate the display element which is inserted within the box. This flat wall portion 26 also facilitates attachment of a hinge element 28 which serves to pivotally connect the cover 4 to the bottom 2 of the box. A spring element 30, connected at one end to one portion of the hinge and at the other end to the other portion of the hinge, acts to resiliently maintain the cover in either open or closed position.

The display element constructed according to the present invention is illustrated in Figs. 2, 3 and 4. It is made in two parts, 34 and 36. The top portion 34 is made of plastic, preferably vacuum formed, and is characterized by a peripheral side wall 35 and a top wall 38 provided with a suitable depression 40 having a shape corresponding generally to the shape of one side of the shaver S which is designed to support. In the illustrated embodiment, the depression 40 is generally of a diamond shape, but, of course, the shape of the depression may be varied according to the particular make of the shaver designed to be encased in the box. At the front, the top portion 34 of the insert element is provided with an upstanding tab 42 by means of which the whole insert element may be grasped and removed from the box.

The bottom portion 36 of the insert element, like the top portion, is also formed of plastic, preferably vacuum formed. The bottom portion comprises generally a side wall 48 conforming in contour to the shape of the inside of the box, it being noted that flat portion 49 is provided conforming to afore described flat portion 26, whereby the insert element will be snugly received within the box and prevented from relative rotation therein. Formed integral with the side wall 48 is a bottom wall or flange 52 whose interior edge is irregular and includes scalloped portions 54 which define an irregular opening 56. The extent to which the flange 52 extends inwardly from the side wall 48 is a matter of choice, being

Fig. 1 is a front view in elevation of a box embody-

sufficiently great to support an electric cord stored therein, but not so great as to leave the opening 56 so small as to restrict ready insertion of the electric cord.

The upper edge of the side wall 48 is undercut to form a groove or shoulder 58 as shown in Fig. 3. Groove 58 accommodates the bottom edge of the side wall 35 of the top portion 34. The two portions 34 and 36 are cemented or otherwise secured together. It is contemplated that the upper portion 34 will not only support the shaver S for display but will also conceal the electric cord C. Accordingly, it is preferred that the upper portion 34 either be made of an opaque plastic, or, as in the illustrated embodiment, the upper portion 34 will be coated with flocked velour, which is shown schematically by the shading 60 in Fig. 2.

Although not necessary, it is contemplated that the depressed portion 40 of the upper section 34 of the insert may be strengthened by ribs 62 so as to better support the weight of the shaver S.

Fig. 3 illustrates how the insert element is used. As packed and shipped by the manufacturer, the box has a cord C coiled within the bottom section 36 and a shaver S resting in the depressed portion 40. When the box is opened, only the shaver S is visible. The cord C is concealed by the top section 34 of the insert so as not to detract from the beauty of the shaver. When it is desired to use the shaver, the insert element is removed by lifting up the tab 42. Then cord C can be removed and attached to the shaver S. To replace the cord is a simple matter: the operator winds the cord around the fingers of one hand in a suitable coil, removes the coil from his fingers and inserts it in the compartment defined by the bottom element 36 of the insert. Then the insert is placed back in the box and the shaver deposited in the depression 40.

It is believed to be apparent that due to the construction of the insert the user will have little difficulty in storing the cord; thus, the user is encouraged to use the box as a depository for the shaver and cord. On the other hand, the retailer will also benefit from the construction of the box since, by reason of the cord being concealed, the shaver itself can be displayed to maximum advantage. Another advantage is that when the insert is removed, the electric cord will not fall out of the insert. Thus, the insert itself can be removed and used as a display stand apart from the box.

It is to be understood that the insert element may be made of material other than plastic and that the shape of the box, and therefore, the exterior shape of the insert, may be varied as desired in accordance with the manufacturer's needs. Similarly, the tab element may be located in a different position and the shape of the depression 40 may be varied in accordance with the shape of the shaver to be displayed.

While this specification sets forth in detail the present and preferred construction, still, in practice, such deviations from such detail may be resorted to as do not form a departure from the spirit of the invention as defined by the appended claims.

I claim:

15. A hollow insert for a box for storing and displaying an electric shaver, said insert comprising integrally molded top and bottom sections, said top section consisting of a top wall having a depression shaped to receive the shaver to be displayed and a depending wall extending marginally therefrom, said bottom section consisting of a peripheral wall connected with and forming a continuation of said top section marginal wall and an inturned flange at the bottom of said peripheral wall defining a relatively large opening at the bottom of the insert, said sections defining an unobstructed compartment to which access may be had through said opening for coiling and storing the shaver electric cord.
20. In combination, a shipping and display box for an electric shaver comprising a body portion having a cover portion hingedly attached thereto, the combination further comprising a hollow insert snugly but removably positioned within said body portion, said insert consisting of a top wall provided with a depression shaped to receive the shaver to be displayed, a depending peripheral wall, and an inturned flange along the bottom of said peripheral wall defining a relatively large opening at the bottom of the insert, said top and peripheral walls and inturned flange defining an unobstructed compartment to which access may be had through said opening for coiling and storing the shaver electric cord.
25. In combination, a shipping and display box for an electric shaver comprising a body portion having a cover portion hingedly attached thereto, the combination further comprising a hollow insert snugly but removably positioned within said body portion, said insert consisting of a top wall provided with a depression shaped to receive the shaver to be displayed, a depending peripheral wall, and an inturned flange along the bottom of said peripheral wall defining a relatively large opening at the bottom of the insert, said top and peripheral walls and inturned flange defining an unobstructed compartment to which access may be had through said opening for coiling and storing the shaver electric cord.
30. In combination, a shipping and display box for an electric shaver comprising a body portion having a cover portion hingedly attached thereto, the combination further comprising a hollow insert snugly but removably positioned within said body portion, said insert consisting of a top wall provided with a depression shaped to receive the shaver to be displayed, a depending peripheral wall, and an inturned flange along the bottom of said peripheral wall defining a relatively large opening at the bottom of the insert, said top and peripheral walls and inturned flange defining an unobstructed compartment to which access may be had through said opening for coiling and storing the shaver electric cord.
35. In combination, a shipping and display box for an electric shaver comprising a body portion having a cover portion hingedly attached thereto, the combination further comprising a hollow insert snugly but removably positioned within said body portion, said insert consisting of a top wall provided with a depression shaped to receive the shaver to be displayed, a depending peripheral wall, and an inturned flange along the bottom of said peripheral wall defining a relatively large opening at the bottom of the insert, said top and peripheral walls and inturned flange defining an unobstructed compartment to which access may be had through said opening for coiling and storing the shaver electric cord.
40. In combination, a shipping and display box for an electric shaver comprising a body portion having a cover portion hingedly attached thereto, the combination further comprising a hollow insert snugly but removably positioned within said body portion, said insert consisting of a top wall provided with a depression shaped to receive the shaver to be displayed, a depending peripheral wall, and an inturned flange along the bottom of said peripheral wall defining a relatively large opening at the bottom of the insert, said top and peripheral walls and inturned flange defining an unobstructed compartment to which access may be had through said opening for coiling and storing the shaver electric cord.
